US00D977517S

(12) **United States Design Patent** (10) **Patent No.:** **US D977,517 S**
(45) **Date of Patent:** **** Feb. 7, 2023**

(54) **DISPLAY SCREEN OR PORTION THEREOF WITH GRAPHICAL USER INTERFACE OR LABEL**

(71) Applicant: **Apple Inc.**, Cupertino, CA (US)

(72) Inventors: **Alan C. Dye**, San Francisco, CA (US); **Lucas Daniel Langhus**, San Jose, CA (US); **Joseph Mark Willoughby Luxton**, San Francisco, CA (US); **Christopher I. Wilson**, San Francisco, CA (US)

(73) Assignee: **Apple Inc.**, Cupertino, CA (US)

(**) Term: **15 Years**

(21) Appl. No.: **29/750,492**

(22) Filed: **Sep. 14, 2020**

(51) LOC (14) Cl. **14-04**

(52) U.S. Cl.

USPC **D14/489**; D20/22

(57) **CLAIM**

The ornamental design for a display screen or portion thereof with graphical user interface or a label, as shown and described.

DESCRIPTION

FIG. 1 is a front view of a display screen or portion thereof with graphical user interface or a label showing the claimed design; and,

FIG. 2 is another embodiment thereof.

The broken lines in the figures show portions of the display screen or portion thereof with graphical user interface or portions of the label that form no part of the claimed design.

1 Claim, 1 Drawing Sheet
